CHARLES R. HOWARD, OF WALPOLE, MASSACHUSETTS

BOOKBINDING

Application filed September 9, 1929. Serial No. 391,212.

This invention relates to book structures and more particularly to the binding of books.

In most books the group of signatures or leaves which make up the body of the book, and in the trade customarily is referred to as the "book", is bound to, and protected by, two covers. The connecting element which secures the book and covers together consists of or includes a super, the central part of which is glued, cemented or otherwise adhesively secured to the back of the book while its margins are overlapped upon and cemented to the inner margins of the cover. 10 Usually a super consists simply of an openly woven fabric, such as unbleached starched cheese cloth. In some cases, however, it is made of firmer material and occasionally, as in text books, two pieces of super are used in order to give added strength, both pieces, however, usually consisting of an openly woven, relatively inexpensive fabric. A better and more expensive binding is made by sewing the signatures or folios to short 20 lengths of tape at the back of the book, and pasting the ends of the tapes to the cover, a super usually being employed in addition to the tapes. This, however, is a construction much less commonly used. The margins of the super are concealed by the lining sheets for the covers, these sheets also giving added security to the union between the super and the covers.

When a book made in this manner is subjected to rough handling it is a very common occurrence for the super to begin to tear at one end of the book, and when such a rupture has been started, the super usually has been weakened to such an extent that 30 considerable care must be exercised to prevent one or both covers from being completely torn away from the book.

The present invention is especially concerned with these conditions. It aims so to improve the binding of books as to increase 40 greatly the strength and wearing qualities of the binding without materially adding to the expense of manufacture.

The nature of the invention will be readily 50 understood from the following description

when read in connection with the accompanying drawings, and the novel features will be particularly pointed out in the appended claims.

In the drawings,

Figure 1 is a perspective view of a book structure embodying this invention;

Fig. 2 is a similar view of a slightly different form of the invention; and

Figs. 1^a and 2^a are diagrammatic views 60 showing the construction of the supers.

Referring first to Fig. 1, the leaves forming the book proper are shown at 2, the covers at 3—3, and the super which holds the leaves of the book together and connects the book with the covers is indicated at 4. In a typical construction each cover consists of a board, such as that shown at 5, covered with a sheet material of some appropriate character, fabric, leather, or the like, ordinarily being used. This material covers the outer surfaces and edges of the board, while the inner surface of the board is covered with a lining material 6, usually of paper. The super 4 may be applied in the usual manner, 70 but it differs from the supers heretofore used in that it includes a series of groups or bands *a* of threads, the individuals of each group or band lying side by side and being closely associated with each other, and adjacent groups being connected by loosely woven sections of the super. The opposite end portions of each of these bands or groups *a* of threads are cemented or otherwise secured to the covers 3—3 while their intermediate 80 portions are secured to the back of the book 2. 75

The entire weight of the super need not be greater than that of supers used heretofore, for corresponding sizes and grades of bindings, the increased number of threads 90 *a* running horizontally from one cover to the other being compensated for by reducing the number of threads that run vertically or parallel to the back of the book. It is obvious that the value of the latter threads 95 lies almost exclusively in their function of holding the transverse or horizontal threads, including the threads *a*, in their proper spaced relationship, and that they have practically no effect in resisting strains tending 100

to tear the book out of its binding. The latter function is performed entirely by the transverse threads. The presence of bands *a* of threads spaced from each other by 5 loosely woven sections of the super has been found to be of peculiar value as distinguished from an arrangement in which the transverse threads are evenly distributed, since a closely associated group of threads is more effective in resisting forces tending to start the tearing of the super. Usually the supers are cut from a web of fabric in a slitting machine and by spacing the bands *a* of transverse thread at relatively close intervals, say 10 for example, one-half or five-eighths of an inch, no substantial tearing of the super can occur before one of these bands of threads is reached. The localized strength or resistance to tearing afforded by such a 15 band is far greater than that found in the usual super.

The cross-sectional construction of the super 4 is illustrated diagrammatically in Fig. 1^a. From an inspection of this figure 20 it will be seen that the bands *a* of transverse threads are interwoven with the vertical threads and because the threads *a* are arranged side by side in a parallel relationship, the overall thickness of the fabric is not substantially greater at the bands than are the 25 intervening sections of fabric. This is of advantage in making a smooth binding and avoiding the presence of ridges.

Fig. 2 shows a similar construction differing 30 from that shown in Fig. 1 only in the nature of the super. Here the threads of the transverse bands *a'* of the super 4' are increased considerably in number, or the bands are made wider, so that the resistance to tearing 35 is increased materially.

It is preferable in weaving both of the fabrics 4 and 4' to have the warp run in the direction of the bands *a*—*a'*, the threads in these bands being warp threads, while those 40 threads running transversely to the bands *a*—*a'* are the filling or weft threads. Assuming, for example, that the super heretofore used for a given purpose has a 28 x 24 weave, that is 28 warp threads per inch and 45 24 filling threads per inch, 8 threads may be taken from the filling and added to the warp, thus making a 36 x 16 fabric, without changing materially the expense of the goods. At the same time the strength of the super in the 50 direction in which strength is required in the book is increased very substantially. If certain of the warp threads are grouped in a manner such as that above described, the effective strength of the super against tearing 55 in the ordinary manner is further increased. An economy in the weaving operation is effected due to the reduction in the number of filling threads per inch. It is preferable, however, to use at least 12 filling threads 60 per inch.

To state the matter somewhat differently, a book bound with a super of this character is given much of the strength of the tape construction, the strength being obtained, however, in a much more economical manner. 70 For a considerable variety of work this construction will eliminate the use of tapes. On the other hand, if the ordinary super gives ample strength for an individual job, a saving can be effected by using a super such as 75 that shown which will have greater transverse strength than the ordinary super but will be more economical because of the difference in construction.

While I have herein shown and described 80 a preferred embodiment of my invention, it will be understood that the invention may be embodied in other forms without departing from the spirit or scope thereof.

Having thus described my invention, what 85 I desire to claim as new is:

1. In a book including a group of signatures, a pair of covers therefor, and a super securing said signatures and said covers together, a super characterized by the fact that 90 said super includes flat bands of closely associated threads which extend across the backs of the signatures, said bands being spaced from each other by intervening loosely woven sections of the super.

2. In a book including a group of signatures, a pair of covers therefor, and a super securing said signatures and said covers together, a super characterized by the fact that 100 said super includes flat bands of closely associated parallel threads extending across the backs of the signatures and securing the signatures to both covers, said super also having widely spaced threads extending transversely to, and interwoven with, the threads of 105 said bands, and additional threads extending approximately parallel to said bands and interwoven with said transverse threads to form loosely woven intervening sections of the super.

3. In a book including a group of signatures, a pair of covers therefor, and a super securing said signatures and said covers together, a super characterized by the fact that 110 said super includes flat bands of closely associated parallel threads extending across the backs of the signatures and securing the signatures to both covers, said bands being spaced from each other by intervening loosely woven sections of the super, and the overall thickness of said super at said bands being approximately the same as that of intervening sections of the super.

4. In a book including a group of signatures, a pair of covers therefor, and a super 125 securing said signatures and said covers together, a super characterized by the fact that said super includes flat bands of closely associated threads which extend across the backs of the signatures, said bands being spaced 130

from each other by intervening loosely woven sections of the super, said bands being so spaced as to locate one of the bands adjacent the top edge of the super, and to locate another of the bands adjacent the lower edge of the super thereby to absorb primary strains in the book.

5. In a book including a group of signatures, a pair of covers therefor, and a super 10 securing said signatures and said covers together, a super characterized by flat, parallel bands of elements, each element being composed of a plurality of closely associated threads, the bands being spaced apart by substantial distances, and the elements in each 15 band being spaced slightly from each other.
